[57] CLAIM

The ornamental design for a stove exhaust vent, as shown and described.

DESCRIPTION

FIG. 1 is a front, top and side perspective view of the stove exhaust vent embodying the design of the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The top of the vent has been shown broken away to indicate indeterminate length.
